UNITED STATES PATENT OFFICE.

JACOB M. BERDAN, OF PATERSON, NEW JERSEY, ASSIGNOR TO JOHNS-MANVILLE INCORPORATED, A CORPORATION OF NEW YORK.

ROOFING.

1,422,526.

Specification of Letters Patent.

Patented July 11, 1922.

Application filed August 4, 1920. Serial No. 401,117.

To all whom it may concern:

Be it known that I, JACOB M. BERDAN, a citizen of the United States of America, residing at city of Paterson, county of Passaic, 5 State of New Jersey, have invented certain new and useful Improvements in Roofing, of which the following is a specification.

My invention relates to roofing built up with several layers of some water-proofed 10 felt, or similar fabric which is usually supplied in rolls and cemented to the roof structure. The invention is particularly applicable to such roofs as have a cement or other monolithic base liable to crack under varying 15 conditions of dryness and temperature, producing expansion and contraction. In such cases it is the practice to cement the layers of felt to the base and to one another, and then, if the base cracks, the superposed 20 felt layers are usually torn apart and a leak in the roof results. My invention overcomes this difficulty by having among the felt layers one member which is composed of two 25 layers, not cemented together over the greater portion of their opposing faces, but otherwise held together sufficiently by some elastic fastening means to prevent the upper layers from being stripped off by the wind or other force.

30 My invention also finds a useful application to roof structures having a wooden base for supporting the layers of waterproof fabric.

The best form of structure embodying my 35 invention at present known to me is illustrated in the accompanying sheet of drawings, in which—

Fig. 1 is a perspective view of a section of roofing constructed in accordance with 40 one form of my invention with parts broken away, or partly separated;

Fig. 2 is a cross section on an enlarged 45 scale of one member of the combination shown in Fig. 1 on line 2—2, of Fig. 1;

Throughout the drawings like reference characters indicate like parts.

1, is the base of the roofing which is usually the deck of the roof structure of a building formed of concrete or similar monolithic 50 material, but may be of wood. 2, represents a layer of cold asphaltic priming material applied to the roof base 1, to serve primarily in producing a cementing surface. Upon this layer are unrolled double members composed of sheets of fabric 3 and 13, which

have been fastened together preferably in the factory where they were manufactured by the rows of stitching 6, 6, through an intermediate layer of loosely felted hair 9. These double expansion elements of the roof 60 structure are slightly overlapped at their edges in the usual manner and then are usually covered by several additional layers of ordinary roofing felt as indicated at 4 and 5, the sheets 3, 4 and 5, being cemented together 65 over their entire opposing surfaces by the usual layers of hot asphalt 7, 7, and the usual top surfacing of hot or cold asphalt is finally applied as indicated at 8.

In use, any cracking of the monolithic 70 base 1, will evidently result, when my invention is employed, in merely tearing apart the lower sheet 13, of the expansion member, leaving the upper sheet 3, and the superposed sheets 4 and 5 intact, as the elasticity 75 of the stitching and the interposed layer of felted hair permits considerable relative movement of the lower sheet 13, without transmission of the same to the upper sheet 3, or to the upper, exposed water-proof layers 4 and 5, which of course are of relatively 80 low tensile strength and consequently must be kept free from the tearing action of the base exerted when the latter contracts and cracks under changes of temperature. 85

The hair felt structure formed by elements 3, 6, 9 and 13, not only forms an expansion layer, by reason of its elasticity horizontally, allowing it to function as above described, but it also serves a most useful purpose as 90 an efficient insulator against the transmission of heat. This function is of the greatest importance when the roofing is applied to a wooden base. It is now generally accepted as an established fact by engineers 95 that much of the rotting of wooden beams and boards in roofs is due to the constant deposition of moisture thereon in cold weather by condensation of the vapor from the warm atmosphere of the building interior, superinduced by the low temperature 100 of the roof, which is exposed to the cold winds or to melting snow of winter. The use of my invention materially reduces this condensation by acting as an insulator 105 against loss of heat from the supporting structure of the roof and so maintaining it more nearly at the temperature of the rooms beneath. This feature of my invention also economizes fuel needed to warm buildings 110

equipped with it in both forms of roof structure here referred to, and is also useful in reducing condensation on the interior of roofs of all forms.

5 My invention also can be employed with roofing prepared for use before application to the building by cementing together the several layers at the place of manufacture.

The intermediate layer of hair felt or 10 other elastic material 9, being of considerable thickness, gives the stitching connecting sheets 3 and 13 a chance to swing one way or the other, as the lower sheet 13 expands or contracts with the roof, without 15 transmitting any appreciable strains to the upper sheet 3, and the elastic body of hair 9 shifts easily upon itself as required.

Having described my invention, I claim

1. A roofing structure having the following 20 parts in combination: a foundation and supporting member, an intermediate member comprising a resilient layer of loosely assem-

bled particles resting directly upon said foundation, and a superposed layer of waterproof fabric of relatively low tensile 25 strength resting directly on said intermediate member, whereby an exposed, elastically supported upper surface is secured and any expansion or contraction of the foundation member is compensated for in the intermediate layer and not transmitted to the superposed waterproof layer.

2. A structure such as set forth in claim 1 in which the said intermediate layer is relatively of considerable thickness and composed of loosely felted fibres.

3. A structure such as set forth in claim 1, in which the intermediate layer is composed of hair felt.

JACOB M. BERDAN.
